UNITED STATES PATENT OFFICE.

VICTOR GELPK AND PAUL KUGEL, OF ZURICH, SWITZERLAND.

BLADE FOR TURBINES.

SPECIFICATION forming part of Letters Patent No. 781,940, dated February 7, 1905.

Application filed July 29, 1903. Serial No. 167,471.

To all whom it may concern:

Be it known that we, VICTOR GELPK and PAUL KUGEL, citizens of the Swiss Confederacy, and residents of Zurich, Switzerland, 5 have invented certain new and useful Improvements in Blades for Turbines, of which the following is a full, clear, and exact specification.

Our invention relates to securing of blades 10 to turbines, and is shown in this application as applied to radially-driven steam or gas turbines.

The accompanying drawings form part of 15 this application, wherein like characters of reference designate like parts throughout the several views.

Figure 1 is a section axially through the blades. Fig. 2 is a radial section through the blades, to the left through the inlet-blades 20 and to the right through the discharge-blades. Fig. 3 shows the working-wheel inlet-blades; Fig. 4, the working-wheel discharge-blades. Fig. 5 shows the distance-pieces, to the left 25 between the working-wheel inlet-blades and to the right between the working-wheel discharge-blades. Fig. 6 shows the discharge-blades with a modified form of securing the distance-pieces. Fig. 7 shows modified forms 30 of the constructions shown in Figs. 1 and 2.

The guide-wheel and working wheel are composed of wheel-bodies *a* and *b* and rings *c c'*, between which the individual blades *d e* and *f g* are held.

As shown in Figs. 1 and 2, the individual 35 blades consist of prismatic pieces, which in section show a sectional view of the blades. At the ends of the individual blades are shoulders *h i*, Figs. 3 and 4, which engage in the retaining-rings *c c'*. Between each two of 40 the shoulders a distance-piece *k* or *l* is provided, which is on the other side formed as a retaining-piece and centers in the turn of the rings *c c'*.

By reference to Fig. 3 it will be seen that 45 the projection or shoulder on the blade is

bounded by lines 1, 2, 3, and 4 and that the distance-piece *k*, Fig. 5, has a correspondingly-shaped recess *h'* to receive the said projection. For the other form of blade (shown in Fig. 4) the projection or shoulder is bounded by lines 5, 6, 7, and 8, while the distance-piece for this shoulder is shown at the right of Fig. 5, the edge 9 being adapted to bear against the side 5 of the shoulder of one blade, while the edge 10 bears against the side 55 7 of the adjacent blades, as indicated in Fig. 2.

It is not essential to my invention that the shoulders have any particular form. For certain cases, Fig. 6, it would be advisable to give the shoulders the form of the blade-sections, in which case the distance-pieces would 60 also be formed like the blade-sections.

The advantage of this invention is readily apparent. It consists in that the individual blades and also the distance-pieces may be 65 made of rolled, drawn, or cast rods and cut out therefrom.

In the form shown in Fig. 7 the blade is provided at its front end with shoulders in the form of round or prismatic tappets *m*, which 70 fit into corresponding openings of the rings *c* and *c'*. In this manner of securing the blades the latter may also be cut out of prismatic rods having the sectional form of the blade.

We do not limit ourselves to the feature of 75 forming the distance-pieces separately from each other, as said pieces may be combined into a continuous ring having openings or recesses therein.

Having now described our invention, what 80 we claim as new, and desire to secure by Letters Patent, is—

1. In combination in a turbine having an annular recess, blades having on both sides 85 projections and distance means fitting in the recess of the turbine and having recesses to receive the projections, substantially as described.

2. In combination in a turbine and with the ring thereof a series of blades having projec- 90

tions and distance means having recesses therein for the said projections, said distance means being carried by the ring.

3. In combination in a turbine, having an annular recess on both sides, blades having on both sides projections, and a ring fitted to the said recess and having recesses to receive the projections, substantially as described.

4. In combination with recessed turbine-
rings, blades having projections and distance-

pieces between the projections and arranged in the said recesses, substantially as described.

In witness whereof we have hereunto set our hands in presence of two witnesses.

VICTOR GELPK.
PAUL KUGEL.
